UNITED STATES PATENT OFFICE.

CLARENCE E. ISACKE, OF NEW YORK, N. Y.

FOLDING DISPLAY-BOX.

No. 823,604.

Specification of Letters Patent.

Patented June 19, 1906.

Application filed April 20, 1905. Serial No. 256,605.

To all whom it may concern:

Be it known that I, CLARENCE E. ISACKE, a subject of the King of Great Britain, and a resident of the city of New York, (borough of Manhattan,) in the county and State of New York, have invented a new and Improved Folding Display-Box, of which the following is a full, clear, and exact description.

The invention relates to an advertising device, particularly to a device for advertising cigars, and it comprises a peculiarly-constructed dummy box, which is formed of paper, cardboard, or equivalent material, and arranged so that it can be shipped flat, thus effecting great economy in space, so that when assembled into proper form and painted or covered with painted or printed sheets it will closely resemble an open box containing cigars.

The advantage in the device lies in the fact that it forms an extremely cheap substitute for the display-boxes commonly used by retail cigar-dealers. In the retail cigar trade it is customary to exhibit boxes of cigars in the show-windows. The cigars so exhibited soon spoil and if not entirely lost to the dealer must be sold at a considerable reduction. By means of my invention this loss is avoided and the dealer is enabled at a much less expenditure to display any number of the dummy boxes.

Reference is had to the accompanying drawings, which illustrate, as an example, the preferred embodiment of my invention, in which drawings like characters of reference indicate like parts in the several views, and in which—

Figure 1 is a perspective view of the device in use. Fig. 2 is a cross-section. Fig. 3 is a fragmentary section through one end of the box, and Fig. 4 is a view of the blank from which the box is formed.

The blank is constructed, preferably, of an integral sheet of cardboard, and it comprises a flap *a*, forming the lid of the box and a section *b*, forming the top wall directly contiguous to the lid-flap or section *a*. At each end of the section *b* flaps *d* are formed, which constitute the ends of the box. On the side of the section *b* opposite the flap *a* a section *c* is formed, which constitutes the front wall of the box, and contiguous to this section is a section *e*, forming the bottom wall. The section *e* has at its outer edge a section *f*, forming the back wall of the box, and this section

f has a tab *g*, projected from its outer edge. The sections *d*, *c*, and *f* have tongues *d'*, *c'*, and *f'* at their outer edges which are adapted to be turned into the box, as will be set forth hereinafter, and serve to hold the parts assembled.

In assembling the box the sections *c* and *f* are bent up from the bottom section *e*, and the top section *b* is bent over the sections *c*, *e*, and *f*, the tongue *g* being run through a slit *h*, formed on the score-line between the sections *a* and *b*. The end walls *d* are then bent down and the tongues *d'*, *c'*, and *f'* are turned into the box, engaging the inner surfaces thereof and holding the parts together.

The outer surfaces of the advertising device are painted, printed, or otherwise provided with illustrations to exactly simulate a box of cigars, and this is shown to some extent in Fig. 1, where a broken stamp is represented and where the top wall or section *b* of the box is painted to represent a layer of cigars. It will also be observed that the tongue *g* projects over the top wall *b* and serves the double purpose of holding the parts together and of representing the paper flap commonly employed in cigar-boxes, this flap extending over the layer of cigars and bearing the makers name or trade-mark. It will be seen that this device can be shipped in flat form to the retailers, and since the cost is very little large numbers of them can be gratuitously distributed enabling the dealer perpetually to advertise the goods without exposing the goods themselves.

Having thus described the preferred form of my invention, what I claim as new, and desire to secure by Letters Patent, is—

1. A folding display-box formed of an integral sheet of material and having top and bottom sections, end sections and side sections adapted to be joined together to form a rectangular box, a flap projecting from the top section whereby to represent the open lid of the box, and a fastening-tongue projecting from the rear side and extending through the sheet of material at the inner edge of said projecting flap, the tongue being located outside of the box and extending over the top wall of the same and representing the name-flap of a cigar-box.

2. A folding display-box formed of an integral sheet of material and capable of being knocked down or laid out flat, said device comprising walls forming when assembled a

six-sided box, and a lid-like wing projecting from one edge or corner thereof, said sheet of material having a fastening-tongue adapted to extend through an opening in the sheet formed at the point of the juncture between said lid-like wing and one wall of the box, the tongue lying outside of the box over the top thereof.

In testimony whereof I have signed my name to this specification in the presence of two subscribing witnesses,

CLARENCE E. ISACKE.
